UNITED STATES PATENT OFFICE.

CHARLES HYMAN, OF GARY, INDIANA.

AUTOMATIC CONTROL MEANS FOR QUENCHING COKE.

Application filed January 7, 1924. Serial No. 684,872.

My invention relates to automatic control means for quenching coke and has particular reference to an automatic control which performs the function of controlling the 5 quantity of water which is sprayed upon the coke after it is taken from the oven, or controlling the length of time the coke is subjected to the quenching operation.

A further object of my invention is the 10 provision of means which automatically controls the quantity of water supplied to a car of coke during a quenching operation, regardless of the pressure of the water, its height in the standpipe or the like.

15 These and other objects of my invention will be further and better understood by reference to the accompanying sheet of drawings, in which—

Figure 1 is a vertical elevational view, 20 diagrammatic in its form, showing the use of my improved invention.

Figure 2 is a vertical sectional view showing the control parts.

Figure 3 is a wiring diagram showing 25 the various electrical control elements.

Figure 4 is a vertical sectional view of a modified form of my invention; and

Figure 5 is a wiring diagram placed convenient to Figure 4 for tracing the electrical 30 circuits which operate the device.

Referring now specifically to the drawings, a standpipe 10 is shown having a main 11 leading therefrom to a quenching house 12, with a spraying arrangement 13 mounted thereon over a car 14 used to contain the coke after it has been removed from the ovens. A master valve 15 is provided, which is controlled by a pilot valve 16, the said valve 15 having a pipe 17 leading from 35 said pilot valve 16 to the master valve 15, with another water pipe 18 leading from the upper side of said pilot valve 16 to the main valve 15 and by means of which said master valve 15 is opened and closed. The 40 said pilot valve 16 has a water supply pipe 19 leading from the main 11 and through which water is supplied through pipes 17 and 18 to the master valve during the operation of the quenching apparatus.

50 All of the above described elements are old in the art and my invention has to do particularly with the control of the water flow through the master valve 15 to the quenching car 14. A house 20 is provided 55 within which is positioned a casing 21 having a solenoid 22 mounted therein and hav-

ing its core associated with the upper end of a connecting rod 23 which is connected to the pilot valve 16, by means of which the master valve 15 is controlled. Connected to 60 the rod 23 is a lever 24 having a plurality of holes 25—25 therein, within which a pin 26 is inserted, the said pin being secured to the side of the casing 21 in any approved manner and may be positioned in any one 65 of the holes 25 to change the amount of movement of the lever arm 24 about the fulcrum point 26. A vertical container 27 is provided having an inlet pipe 28 secured at the upper portion thereof with a valve 70 29 positioned on said inlet pipe, the said valve 29 being controlled by an arm 30, which in turn is secured to a cable 31 which passes over a pair of pulleys 32 and 33 and secured at its opposite end to the lever 24. 75 A member 34 is provided, which is secured to the inlet pipe 28 at the outer end thereof, which has an adjustable orifice therein which controls the rate at which water is delivered to the container 27. At the lower 80 end of the container 27 is an outlet pipe 35 controlled by a valve 36 having an arm 37 secured thereto and to which the cable 31 is fastened at its lower end. A spring 38 is provided which is secured at its lower end 85 to the floor of the house 20 in any approved manner and which has the effect of closing the valve 29 and opening the valve 36 when the solenoid 22 is de-energized, as will be more particularly described hereinafter. 90 Mounted in the container 27 is a float 39 upon a guide rod 40, having a stop 41 mounted upon said guide at its lower portion, the said float 39 having an upwardly extending member 42 projecting upward 95 therefrom and through the top of the container 27. A pair of arms 43 and 44 extend upward from said container with a cross-member 45 extending thereacross and through which an adjusting screw 46 is positioned having a lock nut 47 thereon so that the screw 46 may be locked in any predetermined position. Slidably mounted upon the rod 40 is a conductor 48 which in normal closed position of the circuit rests upon the contact points H and G (Fig. 3), these two contact members being held by the member 49 on the end of the adjusting screw 46, these two contact members H and G being spaced apart with relation to each other to allow the member 42 to pass therebetween and lift the conductor 48 out of 100 105 110

engagement therewith and thereby breaking the circuit to a solenoid mounted on the clapper board as hereinafter described. At the upper end of the plate 45 is a recording cylinder 50 with a rod 51 secured to the float 39 at its lower end and extend upward alongside of the cylinder 50, with a recording needle 52 thereon, the said cylinder being rotated by any suitable clock mechanism (not shown) such as common in these devices.

Referring now specifically to the wiring diagram (Figure 3), an operating switch A is shown which when closed with contact point B, closes the circuit to the clapper solenoid C through the contactor 48 and contact points H and G. As soon as the clapper solenoid C is energized, the contactors L are closed against the contacts I and J, closing the circuit to the solenoid 22, thereby energizing the solenoid causing it to open the pilot valve 16, which in turn opens the master valve allowing the water to flow through to the spraying arrangement 13. The clapper solenoid C also closes the contactor D with the contact points F and E, thus closing this circuit through the contact points H and G and contactor 48. The operator in the meantime has broken the contact A with the contact B, so that the circuit is complete through the solenoid C, contact points F and E through contactor D, and also H and G through the contactor 48 and also through the contact points I and J and contactor L to the solenoid 22.

As hereinafter described, the float 39 as it raises, lifts the contact member 48 out of engagement with the contact points H and G, thereby de-energizing clapper solenoid C and causing the contactor D to be disengaged from the contacts F and E, and also the contactor L to open from the contacts I and J by proper spring pressure mechanism common in devices of this character. The orifice in the member 34 which has been previously adjusted to a predetermined size depending upon the pressure of the water from the source of water supply, controls the quantity of water flowing into the container 27 in a predetermined length of time and which, as the container fills with water, raises the float 39 with its stem 42 until the contact member 48 is lifted from the contact points H and G thus breaking the circuit to the clapper solenoid C de-energizing this solenoid and by proper spring pressure causing it to lift the contact member D from the points F and E, thus opening the circuit to the solenoid 22 which, when de-energized and by gravity, closes the pilot valve 16 which in turn stops the flow of water through the main 11 by closing the master valve 15. At the same time the outlet valve 36 leading into the container 27 is open, the inlet valve 29 is closed by the

spring 38, the water in the container 27 drains out through the discharge pipe 35, the float 39 is lowered bringing the contact member 48 down upon the contact points H and G whereupon the circuit is closed to the clapper solenoid C, the contact member D is again brought into contact with the points F and E, the solenoid 22 is energized and the cycle of operation is repeated as long as the switch A is kept closed. 75

It will be understood that quenching cars are usually pulled through the quenching station and the interval of time which lapses while the water from the container 41 is draining is sufficient to allow the car to be pulled from under the quenching station and another car to be spotted under the spray pipe 13. When it is desired to stop the operation of the apparatus for a considerable length of time the operator opens the switch A thus opening the circuit leading to the clapper solenoid C and causing the apparatus to discontinue its operation.

If for any reason the operator desires to operate the quenching apparatus by hand the switch A is brought into contact with the point B' thus energizing the clapper solenoid C and opening the pilot valve as long as the circuit through the clapper solenoid C is kept closed. When it is desired to stop the sprinkling operation the switch A is opened thus stopping the flow of water through the main to the quenching station. 95

It will thus be understood that the quantity of liquid which passes through the device is controlled by the rate of flow of the water which passes through the orifice in the member 34 into the container 27 and that rate of flow of water is dependent upon the pressure in the standpipe 10. If the pressure in the pipe is low it will take a longer time to raise the float 39 and operate the switch 48 and therefore the flow of water to the quenching car 14 will be continued for a longer period of time than if the pressure in the standpipe is high, thereby forcing the container 27 to fill quickly, so that in any case the quantity of water delivered to the quenching car is controlled by controlling the size of the orifice in the member 34 connected to the supply pipe 28 leading to the container 27. The recording needle 52 makes a record upon the cylinder 50 of each time the float 39 is raised, so that it can be determined with accuracy as to how often during any given period of time the device is operated thus enabling the operator of the plant to determine the number of times the device is operated in any given period of time. 110 115 120 125

In Figure 4 is illustrated a modified form of the device in which a vertical open container 53, having a pipe 54 leading therefrom, which is connected to the supply pipe 28 with the member 34 and having a water 130

supply pipe 55 leading to a valve 56, with an inlet pipe 57 extending into the container 53, the valve 56 being controlled by a float 58 secured upon an arm 59 in the usual manner.

It will be noted that this device serves to maintain a constant level in the container 53 and when it is desired to operate the device the operator closes the electrical circuits 10 in the same manner as heretofore described, which has the effect of draining the water from the container 27 and opening the valve 29. Thereupon the water commences to flow from the container 53 at a predetermined rate of flow, depending upon the size 15 of the orifice in the member 34, and continues until the float 39 is raised to a point where it will break the contact between the points H and G, causing a de-energizing of 20 the solenoid and the closing of the valve 29 and opening of the outlet valve 36, so that the movement of the rod 23 controls the pilot valve 16 and through it the flow of water through the master valve 15 in the 25 usual manner. This latter device is to control the length of time the water is allowed to flow on to the coke for quenching purposes, and is particularly adapted to plants where the water pressure is not constant 30 and wherein it has been determined by calculations previously made as to the length of time required to quench a car of coke.

While I have described more or less precisely the details of construction, I do not 35 wish to be understood as limiting myself thereto as I contemplate changes in form and

the proportion of parts and substitution of equivalents as circumstances may occur or render expedient, without departing from the spirit or scope of my invention.

I claim:

1. The combination with a water main having a master valve, of a pilot valve having an inlet connection with the main and outlet connections leading to opposite sides 45 of the master valve, a solenoid connected to the pilot valve, a float chamber, supply and outlet valves for the float chamber, means actuated by the solenoid for alternately opening and closing the valves of the float 50 chamber, a float in the float chamber, a switch for controlling the solenoid, and means actuated by the float for controlling the switch.

2. In a device of the character described, 55 the combination of a water main having a master valve, a pilot valve having an inlet connection with the main and outlet connections leading to opposite sides of the master valve, a solenoid connected to the 60 pilot valve, a float chamber, supply and outlet valves for the float chamber, means actuated by the solenoid for alternately opening and closing the valves of the float chamber, a float in the float chamber, means for 65 supplying liquid at a constant rate to said float chamber, a switch for controlling the solenoid, and means actuated by the float for controlling the switch.

Signed at Gary, Indiana, this 13th day 70 of December, 1923.

CHARLES HYMAN.
